UNITED STATES PATENT OFFICE.

GEORGES ALBERT LEFORT, OF ST. TITE, QUEBEC, CANADA.

FENCE.

1,232,575.

Specification of Letters Patent. Patented July 10, 1917.

Application filed March 29, 1917. Serial No. 158,224.

To all whom it may concern:

Be it known that I, GEORGES ALBERT LEFORT, a subject of the King of Great Britain, residing at St. Tite, Province of Quebec, 5 Canada, have invented certain new and useful Improvements in Fences; and I do hereby declare that the following is a full, clear, and exact description of the invention, such as will enable others skilled in the art to 10 which it appertains to make and use the same.

The present invention relates to a fence designed to form an obstacle for military defense as a substitute for the ordinary wire 15 entanglements now in use, and an object of the present invention is to provide a portable fence of the character aforesaid whereby the parts thereof may be readily disassembled or assembled and presented for use. 20 With the above and other objects in view which will hereinafter appear as the description continues, the invention consists of the novel features of construction, combination and formation of parts as will be hereinafter 25 more fully described and particularly pointed out in the appended claims.

In the accompanying drawings has been shown the simple and preferred form of the invention, it being, however, understood that 30 no limitation is necessarily made to the precise structural details herein exhibited, but the right is hereby reserved to any changes, alterations or modifications to which recourse may be had that come within the 35 scope of the claims without departing from the spirit of the invention or sacrificing the efficiency of the same.

In the accompanying drawings:

Figure 1 is a perspective view of the fence 40 embodying the present invention;

Fig. 2 is a perspective view of a bracket;

Fig. 3 is a plan view of a blank for forming the bracket;

Fig. 4 is a perspective view of one of the 45 rods;

Fig. 5 is a detail cross section through the rod;

Fig. 6 is a detail cross section through a modified form of the rod;

Fig. 7 is a detail cross section between one 50 of the rods and the bracket showing the fastening means in place for connecting the rod to the bracket; and,

Fig. 8 is a similar view showing the fastening means secured in position.

Referring now more particularly to the

accompanying drawings wherein like and corresponding parts are designated by similar reference characters throughout the several views.

The fence comprises a plurality of sections A each comprising preferably three rods 1 and the sections are adapted to be connected together by means of the ropes or cables B. The rods 1 are preferably formed of sheet 65 metal having their opposite ends pointed as at 2 and their medial portion substantially V-shaped in cross section having the openings 3 formed therein whereby the same may be connected to the bracket 4. The body 70 portions of the rods are substantially M-shaped in cross section as shown in Fig. 5 thereby presenting more edges to view which will make the rods more hazardous. In Fig. 6 of the drawings wherein a modified form 75 of a rod is shown the same is substantially V-shaped throughout its entire length and eliminates the projecting flanges 5 as shown in Fig. 5 of the drawings. The numeral 6 indicates a rivet which is to be inserted 80 through the openings formed within the bracket 4 and the rods 1 for securely holding the same together. In Fig. 7 the rivet as shown is placed in position whereas in Fig. 8 the rivet is shown placed into position 85 and the rods securely fastened to the bracket.

The bracket 4 is preferably made from a piece of sheet metal having substantially a rectangular configuration when in its blank form as shown in Fig. 3. This piece of 90 sheet metal as shown in Fig. 3 is bent along the lines 7 to form a section 8 and the section 9 is bent at right angles to the section 8. The section 10 is bent over upon the section 8 and the section 11 is bent outwardly 95 at right angles to the section 8 thereby forming the structure as shown in Fig. 2. The section 9 is provided with two upwardly projecting tabs 12 and 13, one of which indicated by the numeral 12 acts as a support 100 upon which rests the edge 14 of the section 11 and the tab 13 is bent over the section 11 and locked into engagement with the opening 15 thereby holding the sections of the bracket rigidly together. The edges 16 are 105 bent in opposite directions from the section 11 so that the cables B may be readily connected thereto by inserting the cables through the openings 15 and 15'. In securing the rods to the bracket the medial portion of one of the rods is connected to the section 8 and is arranged parallel thereto.

A second rod is placed upon the section 11 having one flange connected to the section 11 and its other flange connected to the section 8 and the third rod has one flange secured to the lower face of the section 11 and its opposite flange connected to the section 9.

Having thus fully described my invention, what I claim as new and desire to secure by Letters Patent is:

16 1. A fence of the character described comprising a plurality of sections, each section comprising a plurality of rods, each rod being V-shaped in cross section, means for connecting the medial portions of said rods together, and means for flexibly connecting the sections together.

2. A fence comprising a plurality of sections, each section comprising a plurality of rods, a bracket for each section for rigidly connecting the rods together whereby they will extend at right angles to each other and flexible means for connecting said sections together.

3. A fence of the character described comprising a plurality of sections, each section comprising a plurality of rods, said rods being angular in cross section, brackets for connecting the medial portions of said rods together and means whereby cables may be connected to said brackets for the purpose 30 set forth.

4. A portable fence of the character described comprising a plurality of sections, each section comprising three rods arranged at right angles to each other, a bracket for 35 connecting said rods together, said bracket being formed from a single sheet of metal and means for connecting said sections together.

In witness whereof I have hereunto set 40 my hand.

GEORGES ALBERT LEFORT.
